UNITED STATES PATENT OFFICE.

FRANK WILCOMB, OF NORRISTOWN, PENNSYLVANIA, ASSIGNOR TO WILDMAN MFG. COMPANY, OF NORRISTOWN, PENNSYLVANIA, A CORPORATION OF PENNSYLVANIA.

KNITTING-MACHINE.

1,244,268.

Specification of Letters Patent. Patented Oct. 23, 1917.

Continuation in part of application Serial No. 107,617, filed July 5, 1916. This application filed December 13, 1916. Serial No. 136,737.

To all whom it may concern:

Be it known that I, FRANK WILCOMB, a citizen of the United States, and resident of Norristown, Pa., have invented certain new and useful Improvements in Knitting-Machines, of which the following is a specification.

The present specification is a continuation of certain of the subject-matter belonging to the application for Letters Patent of the United States, filed by me July 5, 1916, Serial Number 107,617 and concerns particularly the web holder organization and other features as will be particularly described hereinafter.

The invention consists in the features and combination and arrangement of parts hereinafter described and particularly pointed out in the claims.

20 In the accompanying drawings;

Figure 1 is a vertical sectional view of a machine embodying features of my invention.

Fig. 2 is a side view of the machine or 25 knitting head of Fig. 1.

Fig. 3 is a plan view of the cap of the machine and associated devices.

Fig. 4 is a plan view of a removable sectional gib or ring to permit the removal of 30 needles.

Fig. 5 is a developed view of the web holder cam.

Fig. 6 is a detail sectional view of the means employed in pressing the needle 35 beards.

Fig. 7 is a similar view of a web holder cage.

Fig. 8 is a view of a web ring.

Fig. 9 shows a modification. 40 Fig. 10 is a view of a slightly different construction of knitting head, from that shown in the above figures.

Fig. 11 is a view of a cylinder mounting.

The needle cylinder 1 may be of different 45 forms but for illustrating my invention I disclose one of tapered shape, having the usual guide grooves. The needles are driven by jacks 2 but may be driven by direct engagement with needle cams. These cams are indicated generally at 3.

At the top of the needle cylinder is sup-

ported a web ring 4 having grooves forming continuations of those in the cylinder 1 for guiding the needles and having slots 5 for guiding the web holders 6.

55

The mechanism for pressing the needle beards may assume different forms and still embody my invention therein, but in the particular construction illustrated this presser organization includes a presser wheel, or other member 7, arranged inside of the needle circle or row and means outside said row against which the beards are pressed when the needles are forced or deflected outwardly by the inner presser member or wheel bearing on their backs. The means outside the needle row consists of a ring or cylinder-like body 8 which is supported upon a shoulder 9 of the needle guiding walls of the needle cylinder 1 and to which walls it is clamped by screws 10 seated in a cage 11, hereinafter referred to, the said screws bearing on soft metal plugs or pins 12 mounted in the presser ring. The purpose of these soft metal plugs is to prevent damage to the needle guiding walls to which the presser ring is clamped.

70

The interior surface 12' of this presser ring, which is the presser surface, is at an inclination to the plane or line of the needle 80 movement and though the interior opening of the ring may be flared downwardly its surface converges downwardly with respect to the needle plane, so that as the needle recedes it moves into a progressively contracting space. The invention, as above stated, is not limited to a tapered needle cylinder nor is it limited to the particular shape shown of the interior of the presser ring.

85

The pressing of the beard to pass it 90 through the old loop is effected, as above intimated, by the inner presser member 7 forcing the needle outward against the outside presser ring, holding it in this position until the beard passes entirely through the old loop, after which the inside presser wheel, having passed the needle, releases it, and thus the needle is permitted to resume its normal working place, but the needle beard still remains in contact with the 95 outer surface 12' of the outside presser ring and is thereby prevented from opening.

or at least to such an extent as would cause bursting of the loop, and this continued pressing of the needle beard also has the effect of passing the needle through the loop 5 with the least possible resistance.

The outer presser ring may be formed in sections, or elements having beard pressing surfaces may be arranged in a circle about the needle row.

- 10 The inner presser wheel or member 7 is mounted on a pin 13 of a support 14 depending from an arch-shaped arm 15 pivoted at 16 to a bracket 17 adjustably held by a screw 18 passing through a slot 19 of the bracket 15 into the cap 20 which incloses the knitting elements, as will be made clear hereinafter. This cap is held in place by latches 20^a pivoted on pins 20^a beneath the ring 57 and locked in place by springs 20^b which have 20 projections entering openings in the latches. The springs also serve to hold the latches on their pivots. The arm 15 at its free end is locked in position by a latch 21 pivoted on the screw 22 passing through the bracket 23 25 into the cap or cover 20. The free end of the arm 15 fits in a notch 24 of the bracket 23, Figs. 1 and 3, and the latch works transversely through a notch or slot 25 in the bracket and a notch 26 in the end of the arm. 30 The latch is notched at 27 and when turned by pressure on the finger piece or projection 28, Fig. 3, this notch 27 is brought into line with the free end of the arm 15 and said arm may then be lifted, withdrawing 35 the presser wheel 7 from within the needle row and withdrawing also the yarn feed finger 29 which, as shown in Fig. 1, is carried by the said arm 15.

When the arm is down in position it is 40 locked by turning the latch into the position shown in Fig. 3, this turning movement being effected by pressure of the finger upon the projection 27.

The arm 15 may be adjusted to set the 45 presser wheel in the desired position radially in respect to the needle row by the screw and slot at 18, 19, and for this purpose also the bracket 23 is slotted back to the point 23' to permit the free end of the arm 15 to participate in movement during this adjustment.

Adjustment of the presser wheel circumferentially of the needle row to set it accurately in position for pressing the needles is effected by turning the cap or cover 20 which 55 supports the presser carrying arm 15.

This adjustment is effected by means of a block 28' rotatable on the upper reduced end of the post or standard 29' which, with a like post 29', aids in supporting or sustaining the 60 upper structure containing the knitting elements in proper position, these posts extending up from the base ring 30 as shown in Figs. 1 and 2. The turnable block 28' is grooved or slotted diametrically at 31 and a pin 32 secured to and depending from the

flange of the cap or cover enters this slot, so that by turning the block about the post 29 the pin 32 will be moved and the cap adjusted circumferentially. When the proper adjustment has been made the block can be 70 fixed in position by a set screw 33. It will be understood that only slight adjustment of the inside presser member is necessary.

The system of pressing above described permits removal of the inner presser element 75 so that the machine can be turned around and the needles can be operated without casting off their stitches.

Web holders.

The machine shown is of such small diameter that it has been found impracticable to employ horizontally sliding web holders because their inner ends would nearly or quite meet at the center of the cylinder, which, for 85 illustration, may be only one-half inch in diameter, and no room would be left for the fabric. The web holders 6, therefore, are pivotally mounted at 34 in a plane considerably lower than their nose ends and at points 90 a considerable distance out beyond the circle in which the nose ends lie, so that these nose ends will move in the arc of a circle, the chord of which is sharply inclined downwardly and inwardly, and as shown the nose 95 end and the lower projection of the web holder which ordinarily would constitute the fabric supporting member need not have any movement beyond the inner surface of the web ring 4.

This web holder performs the functions of supporting the newly fed yarn, while the needle is taking it, thus providing a divisional space between the new yarn and the old loop for pressing; preventing the fabric 105 from rising when the needle advances to take the yarn, and feeding the new yarn in position against the needle stem to be taken by the needle beards.

For performing the first mentioned function *i. e.* of supporting the new yarn separated from the fabric loops, the yarn is simply laid on the tops of the web holders and for feeding the yarn against the stems of the needles, preventing it from ballooning and 115 insuring that the beards will seize it, the web holders are provided with abrupt shoulders 37, the vertical faces of which perform the functions just mentioned.

Reverting to the web holder supporting 120 means, the presser ring or unit 8 is provided with a radially slotted enlargement or portion 42 grooved circumferentially at 43 to receive the trunnions 34 on the web holders. The slotted formation guides the 125 web holders and sustains them laterally. The web holders are simply dropped into place and the whole series is held in proper working position by a guard plate or ring 45 which rests on their upper curved tops, 130

which tops or surfaces are concentric with their pivots.

This ring fits within the upper ring 46 of the web holder cage 11 and is held there-by against lateral displacement. It is held down in place by the cap 20.

Any web holder can be lifted out, by removing the cover or cap 20 and then lifting off the guard plate or ring 46, thus giving ready access to all the web holders.

The web holders have their arms 35' guided in slots between the walls 47 of the cage 11, and the outer ends of these arms engage the cam groove or slot 48 of the web holder cam ring 49, which encircles the cage 11, and lies between said cage and the cap or cover 20 needing no other fastening or support. The presser unit 8 forms also a part of the web holder bed, being slotted to receive and guide the web holders and being pinned at 50 to the web holder cage 11. The web holder cam ring has a pin 51 extending out through a notch 52 in the lower edge of the cap or cover 20 and when the cover is turned to adjust the presser wheel 7 to the proper position circumferentially of the needle row, the web holder cam ring is likewise adjusted, by the pin 51.

For adjusting the web holder cam section 49^x, Fig. 5, vertically to get the proper throw of the web holders, I provide a vertically adjustable collar 53 on the post 29', which is adjusted by a nut 54 and held in any adjusted position by a set screw 55. The collar is guided and held against turning by a pin 56 extending down from the ring 57 screwed to the posts 29, 29', said pin passing through the plate 58 on the collar. The collar has pins 59 fixed in its upper plate passing through slots 60 in the ring 57 into the cam section 49^x of the web holder cam ring. Now by adjusting the collar vertically the said cam section will be adjusted also. The pin 51 in this adjusting movement can move up or down in the notch 52 and in all positions it will hold the web holder cam ring in proper circumferential position.

The described presser elements can be used in straight bar machines.

The machine is intended to knit tape and hence its small diameter.

Heretofore there were no tape machines built with sliding or pivotal web holders. Such modifications of pivotal web holders, as devised by me have distinctive location and direction of movement relative to the needles and the cylinder verge. The well known pivoted web holders as located here-
60 tofore would not work on small diameters. The improved web holder is so pivoted that it rocks, not directly across the needle path, but at an acute angle to the needle path. The fabric tail of the web holder is buried 65 in the needle cylinder top slots, not in con-

tact with the fabric, or if it does contact slightly no perceptible obstruction is offered to the free passage of the fabric through the cylinder.

The web holder nose, or hook of the present invention performs the desirable function of holding down the fabric against the upward thrust of the needle, and is better than a radial sliding web holder, such as used in machines of large diameter, because 75 it lifts upward and away from the fabric as it moves backward to permit the new yarn to pass under it, giving the same result which might be obtained with a wide mouth in a common web holder. When the 80 hook descends, its under edge moves to a position close to the needle verge, as shown on the left of Fig. 1 and holds the fabric in a closely defined line giving in this particular, the desirable result obtained with 85 common web holders having extremely small throats under the hooks. Both of these desirable features cannot be obtained with web holders of the common sliding form or those pivoted in the usual way. In this 90 connection reference is also made to Fig. 10 in which the advanced position of the web holder and the close location of its fabric nose to the verge of the needle cylinder is illustrated while the wide or large space to 95 receive the yarn can be seen from the dotted line position *y* of the web holder.

One of the problems to be solved in the design of a tape machine with movable web holders, was to present against the fabric 100 at all times a web holder surface, that when moving, would not saw, or abrade the yarn. A surface bearing against the fabric and having even slightly eccentric movement would not hold closely to the fabric all the 105 time, and would saw the fibers and rupture them at times. The fabric engaging surface is concentric with its pivot and the contact with the fabric is constant and has the minimum abrasive effect, and the degree of pressure is constant for different positions of the 110 web holders.

The web holder fabric surface is so arranged with reference to the cylinder verge, that the concentric arc cuts the corner or 115 verge of the cylinder, without variation of extent since it is concentric, therefore very short loops (the usual requirement) are not strained or cut.

The fabric engaging surface of the web 120 holder stands at an acute angle to the needle stem, therefore as the needle draws new yarn through the loop the inclined fabric surface assists in knocking over or casting off the old loop.

This result has been obtained with sliding web holders, by having an incline on the web holder fabric surface, and in action the fabric is raised by the incline and the knocking over effect is secured. The upward 125 130

movement of the fabric is objectional, and the necessary accurate adjustment of web holder cams makes it impracticable.

The yarn supporting surface of this improved web holder is concentric with its pivot. Owing to the arc being at an acute angle to the needle stem, the relative distance from the place where the new yarn rests, and the needle cylinder verge, is very much greater with a narrow bladed web holder, than with a sliding web holder as usually arranged, unless it has a wide blade. The delivery of the new yarn, from the yarn supporting surface to the fabric surface with my web holder, provides a very narrow gap, or space from one surface to the other for the yarn to snap across, as a small hook is employed, but at the same time a wide division is provided for pressing the beards. A wide horizontal blade provides a wide space between the yarn supporting surface, and the fabric surface, and the stitches must snap from the high plane to the low plane, unsupported, which causes displacement of the loops and causes uneven knitting. My yarn supporting arc surface, presents an acute angle surface to the needle, and the new yarn is held solidly against the stem of the needle where it should be, to be seized by the needle hook as the needle descends. Being a concentric surface, the cam movement on the web holder is not required to be accurately set to keep the yarn at the proper elevation, while a sliding web holder having an inclined surface would need to be very nicely adjusted to preserve the perfect alinement of the inclined surfaces with the needles, and the limit of the web holder's inward movement would be the fabric loops, beyond which the web holder could not go. My yarn supporting surface being concentric with its pivot permits of a wide margin of safety in this respect.

From the above it will be seen that I have provided a web holder organization in which the web holders are pivotally mounted and rock across the needle plane at an acute angle, their fabric tails being buried in the needle cylinder and presenting an unchanging acute angled surface to the fabric loops, the inclined fabric hook having capacity for a wide separation between the new yarn and the old fabric loops, a wide throat measured vertically for receiving new yarn, and a small throat opening to hold the knit courses, the yarn supporting surface at the top of the hook being unchanging in its high position relative to the needles and serving because of its acute angular relation to the needle stems, to hold the new yarn close to the needle stems.

Referring to Fig. 10 it will be seen that the housing or cover 20 rests upon an upward extension of the ring or plate 57, which is secured to the posts 29, 29' extending up

from the rotary cam ring of the machine and this upward extension is provided with a flange 57' which encircles the base of the cover or housing 20 and maintains it against displacement so that this housing remains concentric with the axis of rotation of the machine. This housing has a working fit at A with the surface of the part 46 of the web holder cage and as this web holder cage is secured to the member 8 and as the latter is secured to the needle cylinder it will be seen that the needle cylinder is held at its upper end against displacement from its normal position. This construction prevents any eccentric or wobbling motion at the top of the machine. The needle carrier and the web holder bed with their associated parts constitute a single unit or head which is held by the encircling member 20 against wobbling whether the machine is of the rotary cam type or the rotary needle carrier type.

Referring to Fig. 11 I show a mounting for the lower end of the needle cylinder consisting of a nipple 61 secured by screws 62 to the lower end of the cylinder, the said nipple extending down through a washer 63, which has a lip or flange 64 seated in a recess in the lower face of the frame. The lower end of the nipple is screw-threaded 95 and receives a band nut 65 and this serves to clamp the washer and nipple together, while embracing loosely or movably the adjacent part 64' of the frame. The washer is also engaged by two pins 64a which fit loosely in 100 openings therein, these pins being fixed in the flange of the nipple. The washer carries a contact member 66 adapted to strike against a contact member 67 on the underside of the machine frame. The cylinder fits 105 loosely in its socket 68 of the frame and the washer 63 also is loosely fitted to its seat in the frame, so that the cylinder is not held tight in its seat but is held centrally and against wobbling by the encircling bearing 110 or ring at its upper end, which, in the present instance forms the cover 20 for the parts of the knitting head. The contact of the members 66 and 67 holds the needle cylinder against rotation, it being understood that 115 the form of machine shown in this particular instance being of the rotary cam type.

An advantage of the construction just described is that the operator can have ready access to a defective needle or jack or can 120 position the needle cylinder so that the operation of any particular needle or jack may be observed from the front of the machine. For instance in case the operator desires to remove a defective needle or jack located at 125 the rear side of the cylinder where it is not conveniently accessible it is only necessary for him to turn the machine backward, in which case the needle cylinder will turn with the rotary parts and the defective needle or 130

jack can be brought to the front where the operator is standing and where access can be had to these parts for replacement.

Further, if the operator desires to observe the action of any particular needle or web holder he needs only to turn the machine backward until the defective needle comes to a point where it may be viewed and then the operator by simply holding the nut 65 with his hand can allow the machine to run under power with the cylinder held in this convenient position for observation. After the trouble is located the cylinder may be released to allow the members 66 and 67 to engage and hold the needle cylinder against rotation in the direction of revolution of the machine.

Certain features relating to the needle and jack and rocking implements such as 20 web holders, have been made the subject of other applications, Serial numbers 107107, 107108, 107109 (renewal number 175,211), filed July 1, 1916.

What I claim is:-

25 1. In combination, in a circular knitting machine, a needle cylinder, spring beard needles, and web holders pivotally mounted outside the needle row and having their nose ends describing arcs, the yarn supporting 30 surfaces of the noses inclining downwardly and inwardly in respect to the axis of the needle cylinder, and therefore at an acute angle to the needle stems, and moving along said acute angle, and means to lay the yarn 35 against the needle stems and upon the yarn supporting surfaces of the web holders, substantially as described.

2. In combination in a circular knitting machine, a needle cylinder, spring beard 40 needles, presser means, and pivoted web holders moving at an acute angle to the needle stems and thus presenting their upper yarn supporting surfaces at an acute 45 angle to the needle stems and their lower fabric supporting surfaces at an acute angle to the fabric, means to lay the yarn on the web holders and against the needle stem and means for operating the web holders back and forth while maintaining their acute 50 angular relation to the needles, substantially as described.

3. In combination in a circular knitting machine, a needle cylinder, spring beard 55 needles, means for feeding the yarn directly to the spring beard needles without sinking it between them, presser means, and web holders moving at an acute angle to the needle stems and thus presenting their upper yarn supporting surfaces at an acute angle to the needle stems and their lower fabric 60 supporting surfaces at an acute angle to the fabric, the newly fed yarn lying on said upper surfaces, and means for operating the web holders back and forth while maintaining their acute angular relation to the 65

needles, said web holders having throats, which due to the angular movement present wide openings to receive yarn, and a small opening to hold the fabric against movement as the needle rises when the web holder 70 is advanced, substantially as described.

4. In combination in a circular knitting machine, a needle cylinder, spring beard needles, presser means, and web holders moving at an acute angle to the needle stems 75 and thus presenting their upper yarn supporting surfaces at an acute angle to the needle stems and their lower fabric supporting surfaces at an acute angle to the fabric, and means for operating the web 80 holders back and forth while maintaining their acute angular relation to the needles, said web holders being pivotally mounted and adapted for movement to vary the distance from the cylinder to the web holder 85 nose measured along the acute angular path at different periods in the knitting operation, the yarn and fabric supporting surfaces being concentric with the pivots, substantially as described. 90

5. In combination in a circular knitting machine, a needle cylinder, spring beard needles, means for feeding the yarn directly to the spring beard needles without sinking the yarn between them, web holders 95 having upper yarn supporting noses and lower fabric supporting tails working along lines at an acute angle to the needle stems and with their fabric supporting tails buried in and guided by the needle cylinder, substantially as described. 100

6. In combination in a circular knitting machine, a needle cylinder, spring beard needles, pivoted web holders having their yarn supporting noses and their fabric supporting tails working along lines at an acute 105 angle to the needle stems, their fabric supporting tails buried in the needle cylinder, the fabric supporting edges of the web 110 holder tails being concentric with the web holder pivots and cutting the needle cylinder at the verge thereof, substantially as described.

7. In combination in a circular knitting machine, a needle cylinder, needles, pivoted web holders having their noses and their fabric supporting tails working along lines at an acute angle to the needle stems and with their fabric supporting tails buried in the needle cylinder, the fabric supporting 120 edges of the web holder tails being concentric with their pivots and cutting the needle cylinder at the verge thereof, said web holders being guided in slots in a guiding ring outside the needle cylinder, substantially as 125 described.

8. In combination, needles having spring beards, and web holders movable across the plane of the needle stems and having yarn 130 guarding shoulders substantially parallel to the needle stems to hold the new yarn close

- to the stems without crimping it between them, the needle beards when in normal position to take the yarn being protected against engagement with the yarn by moving between the web holders and out beyond the said parallel shoulders, that are guarding the yarn, substantially as described.
9. In combination, in a circular knitting machine, needles, pivoted web holders with radial arms, web holder cams, a member extending circumferentially of the needle row and web holders, a connection between the said member and the web holder cams which will permit adjustment of a web holder cam vertically on said member, means for adjusting the said cam vertically, means for adjusting the said member circumferentially, and means for rotating the circumferentially extending member continuously in one direction, substantially as described.
10. In combination, in a circular knitting machine, needles, pivoted web holders, vertically movable web holder cams, a member extending circumferentially of the needle row and web holders, a connection between the said member and the web holder cams which will permit vertical adjustment of a web holder cam, and means for adjusting the said member circumferentially, said member serving as a cover for the working parts and being removable vertically, substantially as described.
11. In combination, needles, pivoted web holders, vertically adjustable web holder cams, a member encircling the cams and serving as an inclosure therefor, a connection between the cams and the said member to permit vertical adjustment of the web holder cam and also the removal of the inclosing member, and means for adjusting the web holder cam circumferentially, substantially as described.
12. In combination, needles, web holders pivotally mounted having radially extending arms, a cage or bed slotted for the guidance of said web holder arms, web holder cams outside said cage, an encircling member outside the web holder cams, a support for the cams holding them in position between the cage and said encircling member, means for adjusting the web holder cams vertically and means for adjusting the said encircling member circumferentially to set the web holder cam in proper relation to the needles, substantially as described.
13. In combination in a circular knitting machine, needles, pivoted web holders with radial arms, web holder cams, a member extending circumferentially of the needle row and web holders and rotating continuously in one direction, a connection between the said member and the web holder cams which will permit adjustment of a web holder cam vertically on said member, means for adjusting the said cam vertically and means

for adjusting the said member circumferentially, substantially as described.

14. In combination in a knitting machine, a cylinder, needles, web holders pivotally mounted and having outwardly extending arms, cams vertically adjustable, a web holder bed fixed to the cylinder, a cam supporting ring outside the bed supported on a post, and means adjustably mounted on the post for setting the web holder cam in different positions vertically, substantially as described.

15. In combination, needles, web holders pivotally mounted, a web holder bed or cage, a circumferentially movable cam supporting member, web holder cams connected therewith, to be adjusted circumferentially therewith, posts for supporting said parts, means on one of the posts for adjusting the said member circumferentially, and means on the other post for adjusting one of the web holder cams vertically, substantially as described.

16. A web holder having a throat for retaining the fabric, a fabric guard tongue beneath the fabric, a hook to hold the fabric against movement in the upward direction of the needle, a supporting surface above the hook for the new yarn to provide space for pressing the needle beard, a shoulder projecting above said surface substantially parallel to the needle stem to guide the yarn close to the needle stems without crimping it, substantially as described.

17. In combination in a circular knitting machine, a needle cylinder, spring beard needles, pivoted web holders having their yarn supporting noses and their fabric supporting tails working along lines at an acute angle to the needle stems and with their fabric supporting tails buried in the needle cylinder, the fabric supporting edges of the web holder tails being concentric with their pivots and cutting the needle cylinder at the verge thereof, presser means including an exterior ring against which the beards are pressed, and an inner presser wheel, said web holders being guided in slots in the presser ring, substantially as described.

18. In combination in a knitting machine of the character described, a needle cylinder, a cam ring, web holders at the upper end of the cylinder, means for operating the web holders, a cage surrounding the upper end of the cylinder in which the web holders are supported, said cage being connected with and supported from the upper end of the needle cylinder, a housing surrounding said cage and maintaining the same in proper axial position and supporting means for the housing connected with the cam ring, substantially as described.

19. In combination a needle cylinder extending up from the base of the machine, a cam ring surrounding the cylinder, web

holders, a cage for said web holders supported from and connected with the needle cylinder, a housing having a working fit with the cage and maintaining the same together with the needle cylinder in proper concentric position, a plate supporting the housing and having a portion surrounding the same to hold the housing against lateral displacement and supporting means for the supporting plate connected with the cam ring, substantially as described.

20. In a knitting machine, a needle carrier, independently operated spring beard needles, individual web holders having web holding hooks, said web holders having movement relative to the needle carrier verge to vary the size of the opening between the web holder hook and the needle carrier verge, to provide a wide opening for the reception of new yarn, when the web holders are retracted, and a smaller opening to hold the fabric in a closely defined position while the new loops are being formed, and while the needles are advancing to receive new yarn, and means for feeding the yarn directly to the spring beard needles and onto the upper surfaces of the web holders without sinking the yarn between the needles, substantially as described.

30. 21. In combination in a knitting machine, a needle carrier, spring beard needles, web holders, a presser, means moving the web holder for enlarging the opening between the web holder hook and the carrier verge for receiving new yarn and for reducing the size of said opening after the new yarn is received, to hold the fabric loops in a closely confined position between the hook and the carrier verge, while the needle beard is pressed to pass through the fabric loops, and means for feeding the yarn directly to the spring beard needles and onto the upper surfaces of the web holders without sinking the yarn between the needles, substantially as described.

22. In combination, spring beard needles, web holders movable across the needle path, adjustable cam means to vary the extent of the web holder movement toward the needles, shoulders on the web holders substantially parallel with the needle stems to guide the yarn in a closely defined path close to the needle stems, and to guard the yarn against being engaged by the needle beard as the needle descends to seize the yarn, substantially as described.

23. In combination, spring beard needles, web holders movable across the path of the needles, yarn guiding shoulders on the web holders, cam means for determining the degree of movement of the shoulders (for different size of yarn), with relation to the needles, and to provide a defined path for yarn and a path for the needle beards beyond the path of the yarn, to insure the

seizure of the yarn by the needle as it moves downward and to guard the beard point from engagement with the yarn.

24. In combination in a knitting machine, a needle carrier, needles, movable web holders with fabric surfaces, and guarding tails buried in the needle carrier slots, the said fabric surfaces having a constant degree of pressure against the fabric for different positions of said web holders and unvarying vertical relation to the needle stems at the point adjacent said stems.

25. In a knitting machine, a needle carrier and independently movable needles therein, a cam carrier and needle cams thereon, in combination with pivoted yarn positioning and guarding instruments movable at an angle to the needles, standing pivotally outside the needle row with their fabric ends movable between the needles and having downwardly and inwardly sloping fabric faces and web holding noses projecting between the needles, the size of the yarn and fabric space between the instrument noses and the carrier verge varying according to the position of the instruments.

26. In a knitting machine independently movable spring beard needles, needle and cam carriers and knitting cams, a yarn guide and means to press the needle beards, pivoted instruments mounted on the needle carrier having notches for the fabric and terminating noses movable between each pair of needles and terminal fabric faces sloping at an angle to the needle and extending into the carrier top and yarn positioning and guarding surfaces on the instruments for guiding the yarn against the stems and under the needle beards.

27. In a knitting machine, in combination a needle carrier and spring beard needles, means to move the needles up and down, a yarn guide, a fixed beard presser outside the needle row, a needle deflector inside the needle row to force the needle stems against the needle beards and thus close them during the descent of the needle, instruments intercalated between the needles for supporting the yarn against the stems of the needles without sinking it between them and engaging the fabric to hold the stitches in a substantially fixed position while the needle beards are passing through them.

28. In combination in a circular knitting machine, a needle cylinder, a rotary cam ring, and means for holding the needle cylinder against turning forward with the cam ring but permitting the same to be turned backward with said ring to bring any particular needle to position for observation thereof or access thereto, substantially as described.

29. In combination in a circular knitting machine, a needle cylinder, a rotary cam ring, and means for holding the needle cyl-

inder against turning forward with the cam ring but permitting the same to be turned backward with said ring to bring any particular needle to position for observation 5 thereof or access thereto, and hand grip means for holding the needle cylinder in position while the cam cylinder is turned, substantially as described.

30. In combination in a knitting machine, 10 a needle cylinder, a nipple secured to the lower end of the same and passing through

the base plate, a washer connected with the nipple and bearing on the underside of the base plate, a nut on the nipple to clamp the washer and nipple together, a stop on the washer and a stop on the frame preventing rotation of the cylinder in one direction but allowing it in the other direction, substantially as described.

In testimony whereof, I affix my signature.

FRANK WILCOMB.
